MARIO SOPRANI, OF CASTELFIDARDO, ITALY

SOUND ACTION FOR ACCORDIONS, HARMONICAS AND LIKE INSTRUMENTS

Application filed June 29, 1928, Serial No. 289,170, and in Italy September 9, 1927.

This invention relates to improvements in the construction of accordions, harmonicas and similar instruments and more particularly refers to a novel method of producing the action plate or plates generally used in instruments of this type.

The primary object of this invention is to provide an improved method of producing action plates for accordions, harmonicas and like instruments, whereby the cost of production of the same may be materially reduced.

Another object of the invention is to provide in instruments of the class specified, an action plate or plates of a novel and improved construction, whereby the tonal qualities of the instruments on which said action plates are used are considerably improved.

A further object is to provide an action plate for accordions, harmonicas and like instruments, which by virtue of its construction is stronger and more durable than action plates produced by methods heretofore in use; said action plate being also adapted to be made in more compact form than action plates of the ordinary type having the same number of actions or tones.

Various improvements of my invention are illustrated in the accompanying drawings, in which:

30 Fig. 1 is a plan view of an action plate unit embodying my present invention;

Fig. 2 is a side view in elevation of the same, showing the tongues offset from the plane of the plate by the action of vibration;

35 Figs. 3, 4 and 5 are plan views of similar action plates of various ranges and dimensions;

Fig. 6 is a fragmentary plan view of a multiple action plate showing the possibility 40 of producing a considerable range of tones by the use of a single metal plate; and

Fig. 7 is a fragmentary side view in elevation showing the preferred method of producing a multiple action plate such as illustrated 45 in Fig. 6.

In Figs. 1 and 2, I illustrate action plates embodying my invention, in which the tongues are formed integral with the plate.

50 In said figures 1 and 2, 13 designates a plate cut out of the sheet metal of suitable thick-

ness, and 14, 15 designate two vibrating tongues obtained by slitting the metal across the outer edge of each tongue as shown at 16, and along its longitudinal edges 17, 18, leaving each tongue attached to the body of the 55 metal at the rear as shown at 19.

The entire device being thus made out of a single piece of metal, it can be produced at a single operation and with far greater accuracy than it would be possible to obtain 60 if the tongues were produced separately and attached to the plate as is now generally done. A considerable saving of material will be realized because there will be no scrap resulting from the separate production of the 65 tongues and no rivets are required; furthermore, a proportionate saving of labor is also effected.

The principal advantages to be derived 70 from this method of construction however, reside in the improved performance of an instrument equipped with action plates made according to my invention, and in the possibility of reducing the size of the instrument 75 without reducing its range. In fact, the possibility of the tongues becoming loose is absolutely prevented since the same are integral with the body of the plate. The interstices of clearances intervening between the edges of the tongues and the plate are reduced to 80 an absolute minimum, since the slitting operation produces edges which are practically adjoining; therefore the tongues will vibrate with greater intensity.

In addition it will be observed that the 85 tendency of a tongue to break close to its point of attachment is corrected or diminished due to the superior character of the connection thus obtained.

Another advantage which may be realized 90 is that the width of material intervening between two adjoining tongues may be made very small. It is therefore possible to proportionately reduce the length of the action plate as well as the length of the corresponding key board where a plurality of such action plates are employed, the result being a 95 very compact instrument easy to handle.

In Figs. 3, 4 and 5, I illustrate the possibility of applying my improved method of 100

production in connection with action plates of different sizes and types; for instance, in Fig. 3, I illustrate an action unit comprising a plate 20 and two tongues 21, 22 integral therewith, said tongues tapering down from their point of attachment to the opposite end; in Fig. 4, I illustrate a similar unit comprising a plate 23 and two short tapering tongues 24, 25, such as may be employed for the higher pitched notes; and in Fig. 5, I illustrate a single action unit comprising a plate 26 and a single tapering tongue 27 integral therewith.

My invention may also be applied in producing multiple action plates which may be formed in one piece to extend, if desired, from one end of the keyboard to the other.

Such a possibility is illustrated in Fig. 6 where 28 designates a plate decreasing in width from the low pitched to the high pitched end of the board, said plate being provided with a plurality of actions each comprising two vibrating tongues 29, 30 decreasing in length from one end to the other of said plate.

It will be observed however, that in practice, the tongues used for the production of low pitched notes, are not only longer, but are also thicker than those used for the production of high pitched tones; so that metals of various gauges are used for the production of a complete set. This condition may be duplicated in carrying out my invention without sacrificing the advantages due to my method of production, by using a plate having a decreasing thickness from the low pitched to the high pitched end as shown in Fig. 7, where the left end 28' of plate 28 is not only wider but is also thicker than the right end 28'' of the same plate.

It is, of course, possible to produce vibrating tongues of various types and shapes merely by changing the outline of the corresponding slit through the plate, so that various unusual notes may be produced if desired, which could not easily be obtained by the methods heretofore in use.

My improved action plates may be made out of any suitable metal and gauge and may be either made in the form of elementary units or in the form of sectional or complete units without departing from the scope of my inventive idea.

It is obvious that minor details of construction may vary from those shown without departing from the spirit of my invention; therefore, I reserve the right to carry my invention into practice in all those ways and manners which may enter, fairly, into the scope of the appended claims.

I claim:

1. An action unit for musical instruments of the character specified, comprising a plate slit according to a predetermined outline, so as to form a vibrating element integral with

said plate, both surfaces of said element being substantially even with the surfaces of said plate.

2. An action board for musical instruments of the character specified, comprising a plate split at spaced positions intermediate its ends, so as to form a series of vibrating elements being capable of producing sounds of gradually varying value, both surfaces of said elements being substantially even with the surfaces of said plate. 75

3. An action board for musical instruments of the character specified, comprising a plate split at spaced positions intermediate of its ends, so as to form a series of vibrating elements having a gradually decreasing length, and having both of their surfaces substantially even with the surfaces of said plate. 80

4. An action board for musical instruments of the character specified, comprising a plate having a gradually decreasing thickness from one of its ends to the other, said plate being split at spaced positions intermediate its ends, so as to form a series of vibrating elements, integral with said plate, said vibrating elements having a gradually decreasing thickness, and having both of their surfaces substantially even with the surfaces of said plate. 85

5. An action board for musical instruments of the character specified, comprising a plate having a gradually decreasing thickness from one of its ends to the other, said plate being split at spaced positions intermediate its ends, so as to form a series of vibrating elements integral with said plate, said vibrating elements having a gradually decreasing length and a gradually decreasing thickness, and having both of their surfaces substantially even with the surfaces of said plate. 90

In testimony whereof I affix my signature. 105
MARIO SOPRANI.
